(57) **CLAIM**

The ornamental design of a product display rack, as shown.

DESCRIPTION

FIG. 1 is a front and side perspective view of an embodiment of a first embodiment of a product display rack according to the present invention.

FIG. 2 is an elevation left side view (when viewed from the front) of the product display rack of FIG. 1.

FIG. 3 is an elevation right side view (when viewed from the front) of the product display rack of FIG. 1.

FIG. 4 is an elevation back view of the product display rack of FIG. 1.

FIG. 5 is an elevation front view of the product display rack of FIG. 1.

FIG. 6 is a top view of the product display rack of FIG. 1.

FIG. 7 is a bottom view of the product display rack of FIG. 1.

FIG. 8 is a front and side perspective view of a second embodiment of a second embodiment of a product display rack according to the present invention.

FIG. 9 is an elevation left side view (when viewed from the front) of the product display rack of FIG. 8.

FIG. 10 is an elevation right side view (when viewed from the front) of the product display rack of FIG. 8.

FIG. 11 is an elevation front view of the product display rack of FIG. 8.

FIG. 12 is an elevation back view of the product display rack of FIG. 8.

FIG. 13 is a top view of the product display rack of FIG. 8.

FIG. 14 is a bottom view of the product display rack of FIG. 8.

FIG. 15 is a front and side perspective view of a third embodiment of a product display rack according to the present invention.

FIG. 16 is an elevation back view of the product display rack of FIG. 15.

FIG. 17 is a top view of the product display rack of FIG. 15; and,

FIG. 18 is a bottom view of the product display rack of FIG. 15.
